MOSS E. GRAVES AND CARL C. SEVERIN, OF SAN FRANCISCO, CALIFORNIA.

HIGH-TENSION OPERATING SWITCH.

Application filed December 27, 1922. Serial No. 609,224.

To all whom it may concern:

Be it known that we, Moss E. GRAVES and CARL C. SEVERIN, citizens of the United States, residing at the city and county of San Francisco and State of California, have invented new and useful Improvements in a High-Tension Operating Switch, of which the following is a specification.

This invention relates to air break switches such as are used for opening the circuits of high tension transmission lines, and especially to improvements in the structure of the switch shown in our copending application entitled "High tension operating switch," filed December 14, 1921, Serial No. 522,445.

The object of the present invention is to generally improve and simplify switches of the character described; to so dispose the dielectric parts of the switch that they may be adapted to not only withstand the destructive electrical stresses to which they are exposed, but that they may also successfully withstand the mechanical stresses to which they are frequently subjected; to reduce the number of insulating units required to a minimum; to reduce the number of mechanical parts required to a minimum; to provide a switch in which the arcing period when opening the switch is reduced to a minimum by a quick break mechanism; a switch in which the breaking distance can be readily increased or decreased relative to the height of the supporting poles or towers; a switch which may be opened by gravity and closed by counterweight action; a switch which is automatically grounded when in open position, and which may be wiped and tested without killing or grounding the line, thereby saving labor and eliminating line hazard to workmen. Further objects will hereinafter appear.

One form which our invention may assume is exemplified in the following description and illustrated in the accompanying drawings, in which—

Fig. 1 is a side elevation of the switch and a pole or tower supporting the same.

Fig. 2 is an end elevation of the switch and the tower.

Fig. 3 is an enlarged detail view partly in section, showing the quick break mechanism.

Fig. 4 is a cross section on line 4—4, Fig. 3.

Fig. 5 is a detail view of the movable part of the switch.

Fig. 6 is a cross section on line 6—6, Fig. 3.

Referring to the drawings in detail, and particularly to Figs. 1 and 2, A indicates a suitable support, for instance such as may be provided by means of a transmission line tower or pole as here illustrated. The transmission line in this instance is a three-phase line, the separate lines being indicated at B, C and D. Each line is dead-ended with relation to the pole by means of dead end insulators as indicated at 2 and 3; the insulators provided being of the disk or suspension type and being secured to the pole by eye-bolts or the like as here illustrated. Disposed transverse of the line and positioned directly below the same is a vertically movable switch, generally indicated at E. This switch consists of a transverse bar 4, which is supported by a frame, consisting of uprights 5 and a transverse bar 6. The uprights are guided by rollers 7 and the transverse bar is connected to a pole or rod 8, with which is connected means for raising and lowering the switch frame, said means will hereinafter be referred to. Secured to the lower side of the transverse bar 4 are three sets of insulators, generally indicated at 9, 10 and 11. These insulators are of the rigid suspension type and each string of insulators supports an auxiliary switch frame 12. These frames are disposed below the line wires and are positioned parallel with the same; each frame serving the function of connecting the lines when a circuit is to be closed.

The auxiliary frames are identical in construction and the description of one will therefore suffice for all. By referring to Figs. 1, 3 and 5, it will be seen that each auxiliary frame consists of a pair of upright tubular members 13 connected by a horizontal tubular member 14, which in turn is centrally supported by the bar 4 and the string of insulators. The uprights 13 are braced with relation to the horizontal member 14 by means of angle braces 15, and each upright member serves as a guide and receptacle for a plunger rod 16, which is nor-

10 mally held in depressed position by means of a lower collar 17 and an interposed surrounding helical spring 18. There is one plunger rod 16 in each upright 13, and each plunger carries a switch member generally indicated at 19. The switch members employed in each instance are identical. They consist of three flexible fingers or copper blades 20, which terminate in carbon tips 21, see Figs. 3 and 5. There are three sets of fingers disposed on each side and these fingers serve the function of forming a contact with the line when the switch is closed. The fingers are secured to a head member 22 15 disposed on the upper end of the plunger 16 and this head member in turn supports a flexible jumper cable 23, the opposite end of which is connected to a clamp 24 secured on the upper end of the respective uprights 20 13. These clamps are in turn connected by a wire or cable 25, and a complete circuit is thus formed between the fingers 20 and the ends of the line when the switch is closed. The only reason for employing 25 cables such as indicated at 23 and 25, is to avoid poor contacts, that is, if the auxiliary frame were depended upon for a conductor, it would be obvious that more or less arcing or burning would take place when the plungers 16 are extended and retracted, such 30 burning is avoided by the use of the cables referred to.

For the purpose of producing a quick break switch, a pivotally mounted contact lever 26 is employed. This lever terminates in a rounded end 27, which is engaged and gripped by the fingers 20 when the switch is closed. The opposite end of the lever is pivotally secured, as at 28, to a clamp 29, 40 which is turnably mounted on a ferrule or bushing 30 secured directly to the line. Stop collars 31 secured to this bushing prevent endwise movement of the clamp 29 and the lever 26 and perfect contact with the lever, 45 without passing through the ferrule and the clamp 29, is obtained by a jumper connection 32. A spring is also attached to the lever as indicated at 33 and this spring serves the function of normally maintaining 50 the contact end 27 in parallelism with the line or in the position shown in Fig. 3. The contact end is furthermore guided to maintain such parallelism by means of a clamp 34, which terminates in V-shaped guiding 55 arms 35, see Fig. 4.

In actual operation with the switch in closed position, as shown in Figs. 1, 2 and 3, a circuit will pass from the line wire D through the jumper 32, arm 26, fingers 20, jumper wire 23, wire 25, then through 60 the opposite jumper 23, and fingers 20 which engage the opposite lever 26. The current then passes through this lever and the jumper indicated at 32 and finally enters 65 the opposite end of the line indicated at

D'. A perfect circuit is maintained by the jumper wires shown and arcing or burning between movable parts is thus prevented, that is, the jumper wire 32 makes a perfect contact with the levers 26, thus avoiding 70 burning at the pivotal connection 28. The wires 23 similarly form positive connections between the fingers 20 and the wire 25, thus avoiding burning or arcing when the plungers are reciprocated as will hereinafter 75 be described.

It should, therefore, be obvious that the only parts of the switch which will be subjected to any arcing or burning action are the parts represented by the contact ends 80 of the levers 26 and the fingers 20, however means are employed for quickly breaking contacts when opening the switch. This is accomplished in the following manner:

When the switch is to be opened, the main frame E is rapidly lowered. During this lowering action a fairly secure grip is maintained between the fingers 20 and the contacting ends 27 of the levers 26. The plungers 16 will, therefore, raise in their respective guides 13, and the levers 26 will, at the same time, swing about their pivotal connections 28. The tension on the springs 33, and similarly the tension on the springs 18, however, rapidly increases during the lowering of the main switch frame and as this is the case a point is obviously reached where this spring tension overcomes the gripping tension of the fingers 20. The contacting ends 27 of the levers 26 are thus 100 released and the levers 26 are instantaneously returned to assume their normal horizontal position, due to the springs 33. The plungers 16 carrying the fingers 20 are, at the same time, returned to retracted normal position by the springs 18, and as the switch frame is simultaneously traveling in a downward direction with rapid movement, it is obvious that the 105 actual time required to break the circuit is reduced to a minimum, that is, the return of the arms 26, when released, is almost instantaneous, and similarly the return of the plungers 16 which carry the fingers 20. This rapid separation or return of the 110 separate members of the switch is of great importance as it reduces the arcing period to a minimum, that is, an arc is always formed during the separation of the contacts in a switch of this character, and it is 115 therefore exceedingly important to reduce the time of the arcing period as much as possible. In this instance the actual time of separation and return of the members to normal position takes place in a small fraction of a second and destructive burning of the contacts is thus avoided. In fact the 120 only parts which are subject to burning are the outer ends of the fingers 20, and as these are carbon tipped as illustrated, it is 125

130

obvious that the tips may be renewed whenever required.

The present invention also embodies a novel method of opening and closing the switch. This is accomplished as follows:

Disposed at the bottom of the pole or tower, indicated at A, is a circular, cylindrical casing F. Disposed at the respective ends of the casing are hinged doors 41 and 42, each of which is adapted to be locked, and extending through the upper end of the casing is a cable 43, which carries a weight 44 in its lower end. The opposite end of the cable passes over a guide pulley 45 and is then secured to the lower end of the switch frame rod 8. If the switch is opened and assumes the dotted line position indicated in Fig. 1, and it is desired to close the switch, it is accomplished by first securing the cable 20 by means of a clamp 46. The upper door 41 is then opened by means of a key and a series of counterweights 47 are placed on the weight 44; the number of counterweights placed thereon being more than sufficient to 25 raise the switch therefrom. When these weights have been placed in position, it is only necessary to close the door 41 and then to release the clamp 46. The weights will then travel downwardly in the casing F and 30 will finally assume the full line position shown in Fig. 1 in the lower end of the casing. The switch will simultaneously be raised to assume the full line position shown and a circuit is thus closed between the contacts previously described. If the switch is 35 closed and it is desired to open the same, a reverse operation takes place, that is, the clamp 46 is again secured. The lower door is opened and the counterweights 47 are removed. The door is again closed and locked and the clamp 46 is then released. The 40 weight of the switch frame is now sufficient to cause it to drop by gravity and as it will drop rapidly, due to the removal of the counterweights, it is obvious that the contacts 20 and 27 will separate with a snap and reduce the arcing period to a minimum. This method of opening and closing the switch is important from several points of 45 view: first of all, if there should be a short circuit of any kind in the tower or supported structure the operator would not be greatly endangered, as his only duty is either that of applying or removing the counterweights, as 50 the case may be, and then releasing the clamp 46. In other words, he does this before any movement is imparted to the switch and as he can step away the moment the clamp 46 is released, it is obvious that all 55 danger is avoided as the opening or closing of the switch thereafter will be automatically taken care of.

The switch opening and closing means are of further importance as tampering by unauthorized persons is prevented; that is, the

switch is locked either in an open or closed position when the doors 41 and 42 are closed; and as these doors can only be opened by a key, it is obvious that they can not be tampered with, as only an authorized person will carry the key. Means are also provided for further safeguarding the operator or the workmen as the ground circuit is automatically closed when the switch is lowered to open position; that is, a pair of contacts 50, which are grounded as shown in Fig. 2, engage the main switch frame when this is lowered and as such grounds the same. This is, obviously, of great importance as it will permit the line-men to wipe the insulators and to repair and test the switch without danger of being subjected to current shocks or otherwise.

The present structure, as previously stated, is an improvement on our co-pending application already referred to. It contains several features which are important when comparison is made therewith. First, it can be seen that the structure as a whole is exceedingly simple and substantial in construction; that comparatively few switch parts are employed and such as are employed are of standard construction and readily obtainable. Secondly, the number of insulators employed is reduced to a minimum as only one string of insulators, such as shown at 9, 10 and 11, will be required for each sub-frame. A high degree of insulation is in this manner obtained as insulators of the rigid suspension type may be employed and as only one unit is required for each frame, it is obvious that the cost, as far as insulation is concerned, is reduced to a minimum. Third, by employing the quick break mechanism illustrated, arcing between the contacts is practically avoided, as the break is so quick or rapid that, even though arcing does take place, it is for such a short time period that no material damage can be effected. Fourth, practically any breaking distance 105 may be obtained, first by increasing or decreasing the vertical movement of the switch, and secondly by increasing or decreasing the distance between the respective sets of contact fingers 20. Exceedingly high 110 voltages can, therefore, be readily taken care of. Fifth, all movable parts employed are dead and grounded when the switch is opened and as this is the case all hazard or danger to the line-men or workers is eliminated when the switches are being inspected, 115 wiped, repaired, etc.

While certain features of the present invention are more or less specifically illustrated, we wish it understood that various 120 changes in form and proportion may be resorted to within the scope of the appended claims, similarly that the materials and finish of the several parts employed may be such as the experience and judgment of the 125

manufacturer may dictate or various uses may demand.

Having thus described our invention, what we claim and desire to secure by Letters Patent is—

1. The combination with a high potential transmission line and a support therefor having insulating units dead-ending the line with relation to the support, of a switch member movable to and away from the line, and a quick break mechanism carried by the switch and adapted to make or break a circuit through the line.
2. The combination with a high potential transmission line and a support therefor having insulating units dead-ending the line with relation to the support, of a switch member movable to and away from the line, and a quick break mechanism carried by the switch and the line and adapted to make or break a circuit through the line.
3. The combination with a high potential transmission line and a support therefor having insulating units dead-ending the line with relation to the support, of a switch member movable to and away from the line, contact members carried by said switch and engageable with the line to close a circuit therethrough, and means for automatically grounding the switch when the circuit through the line is broken.
4. The combination with a high potential transmission line and a support therefor having insulating units dead-ending the line with relation to the support, of a frame vertically movable on the support, guide rollers engaging the frame, a switch frame disposed at right angles to the first named frame and suspended from said first named frame by means of insulators disposed at one point, and contacts carried by said switch frame and engageable with the line wires to close a circuit therethrough.
5. In a switch of the character described the combination with a support and a frame vertically movable thereon, of a single insulating unit carried by said frame, and a switch frame secured to and carried by said single insulating unit.
6. In a switch of the character described the combination with dead-ended line wires, of a clamp carried by each line wire and freely turnable thereon, an arm pivotally mounted in each clamp, spring means normally holding the arms in parallelism with the line wires, and a switch member movable into and out of engagement with said levers to make or break a circuit through the line.
7. In a switch of the character described the combination with dead-ended line wires, of a clamp carried by each line wire and freely turnable thereon, an arm pivotally mounted in each clamp, spring means normally holding the arms in parallelism with

the line wires, a switch member disposed in parallelism with the line and below the same, a pair of plungers, one at each end of said switch member, and said plungers being normally spring retracted, contact members on the upper end of each plunger and engageable with the levers carried by the line, and means for raising and lowering the switch frame with relation to the line wires.

8. In a switch of the character described the combination with dead-ended line wires, of a clamp carried by each line wire and freely turnable thereon, an arm pivotally mounted in each clamp, spring means normally holding the arms in parallelism with the line wires, a switch member disposed in parallelism with the line and below the same, a pair of plungers, one at each end of said switch member, and said plungers being normally spring retracted, contact members on the upper end of each plunger and engageable with the levers carried by the line, a conductor wire carried by the switch frame, a jumper connection between each end of said wire and the plunger contacts, and a jumper connection between each lever contact and its adjacent line wire.

9. In a switch of the character described a vertically movable switch member, a pulley, a cable passing over the pulley and having one end attached to the switch member, a weight on the opposite end of the cable, an elongated casing in which said weight travels, a door at each end of the casing, means for locking each door, means permitting addition or removal of counterweights to the first named weight, and means for releasing or clamping the cable against movement.

10. In a switch of the character described the combination with dead-ended line wires, of a switch frame vertically movable with relation to the line wires, a quick break attachment disposed on each end of the switch frame, a quick break cooperating switch member carried by each line wire, and means for imparting a vertical movement to the switch frame.

11. In a switch of the character described the combination with dead-ended line wires, and a support therefor, of a ferrule secured to each line wire, a clamp turnably mounted on each ferrule, a lever carried by each clamp and pivotally secured thereto, spring actuated means normally maintaining said levers in parallelism with their respective line wires, a jumper connection between each lever and adjacent wire, and a switch member movable to and away from said levers.

12. In a switch of the character described the combination with dead-ended line wires, and a support therefor, of a ferrule secured to each line wire, a clamp turnably mounted on each ferrule, a lever carried by each

clamp and pivotally secured thereto, spring actuated means normally maintaining said levers in parallelism with their respective line wires, a jumper connection between each 5 lever and adjacent wire, a switch member movable to and away from said levers, and a quick break contact member disposed on each end of said switch member and engageable with the pivotally mounted levers to make or 10 break a circuit through the line wires.

13. In a switch of the character described the combination with dead-ended line wires, and a support therefor, of a ferrule secured to each line wire, a clamp turnably mounted

on each ferrule, a lever carried by each 15 clamp and pivotally secured thereto, spring actuated means normally maintaining said levers in parallelism with their respective line wires, a jumper connection between each lever and adjacent wire, a switch member 20 movable to and away from said levers, a single insulating unit supporting the switch member, and means for imparting a vertical movement to said insulating unit and the switch member.
